UNITED STATES PATENT OFFICE.

GEORGE E. BEACH, OF GLENROCK, WYOMING

AUTOMATIC ALARM.

1,268,422.

Specification of Letters Patent.

Patented June 4, 1918.

Application filed March 26, 1917. Serial No. 157,495.

To all whom it may concern:

Be it known that I, GEORGE E. BEACH, a citizen of the United States, residing at Glenrock, in the county of Converse and State of Wyoming, have invented certain new and useful Improvements in Automatic Alarms, of which the following is a specification.

This invention relates to automatic alarm 10 for brooders and incubators and the primary object of the invention is to provide automatically operated means for sounding a signal bell when the heat in the incubator or brooder varies above or below a certain 15 desirable predetermined temperature.

One of the objects of the invention is to provide an electrically operated device associated with a heating unit within the brooder whereby the diminishing or increasing 20 heat from the said unit will act to close an electric circuit whereby the signal bell will be sounded.

The above and additional objects are accomplished by such means as are illustrated 25 in the preferred embodiment and in the accompanying drawings, wherein like characters denote like or corresponding parts throughout the several views, in which;

Figure 1 is a side elevation of a brooder 30 or incubator partly broken away to disclose the interior having my invention arranged therein.

Fig. 2 is a fragmentary vertical section on the line 2—2 of Fig. 1.

Referring to the drawing, wherein is illustrated the preferred form of my invention, and in which like numerals of reference indicate corresponding parts throughout the several views, the brooder or incubator 1 is 35 of any preferred construction and is provided on its interior with a heat generator 2 which, in this instance, is in the shape of a lamp burning any suitable fuel. Mounted upon the wall 3 of the incubator is a bracket 40 4 upon the end of which is pivoted a balancing beam 5. One end of the beam is provided with a hook 6 to which is connected an eye bolt 7 and this eye bolt carries a pair of superposed disks 8 and 9, which are held 45 in spaced relation by a short sleeve 10. The disk 8 is considerably smaller than the disk 9 and by referring to Fig. 1 of the drawing it will be noted that this disk is suspended directly over the top of the chimney which 50 is carried by the heating unit 2. This causes both of the disks to be subjected to the

waves of heat which rise through the chimney for the purpose of heating the interior of the incubator. The disk 9 is of a larger diameter so that a greater heat receiving 60 surface is presented. The opposite end of the beam 5 carries a weight 11 whereby the beam is suitably balanced when in operative position.

The interior of the brooder is provided 65 with supporting cross pieces 12 of wood or any other suitable material and one of these cross pieces carries a vertically adjustable stem 13 which is projected through an opening formed in the said cross piece and held 70 in adjusted position by a suitable set screw. The lower end of this stem is disposed directly above the eye bolt 7 so that upward movement of the beam 5 will cause the eye-bolt to contact with the stem 13. Mounted 75 in the other cross piece 12 is a comparatively longer stem 14 which is adapted to be vertically adjusted and is held in fixed position by a suitable set screw mounted in one of the cross pieces. This stem 14 has its lower 80 end provided with a finger 15 which projects inwardly beneath the edge of the disk 9 so that downward movement of the end of the beam 5 will bring the edge of the disk 9 into contact with the finger 15.

Arranged at any suitable point within the brooder is a source of current in the form of electric batteries B and the electric conductors from these batteries have one of their terminals fixed to the plate 9 90 while the opposite terminal is connected to a suitable electric conductor 16 the ends of which are in contact with the stems 13 and 14. A signal bell 17 and a suitable switch 18 are properly connected and arranged in 95 the circuit from the batteries B.

In operation, the heat generating unit 2 will be ignited and permitted to burn until a suitable temperature has been obtained within the incubator. Since the heat waves from the open top of the chimney will act upon the disks 8 and 9 and give them a tendency to rise, the weight 11 will be adjusted so that the beam 5 will be balanced in a position to maintain the disks at the proper height above the top of the chimney. As soon as the heat becomes too great, the disks will be raised by the heat waves and contact with the stem 13 will be made thereby closing the circuit, the switch 18 being previously closed, and causing the signal bell 17 to be energized. When the temperature

goes too low, the disks will begin to drop and the small disk 8 will pass into the open end of the chimney and the other disks will contact with the finger 15 thereby again closing the circuit established through the stem 14 and its contact with the conductor 16 and causing the bell to be energized.

Since the decrease in the temperature will be caused by the supply of fuel being exhausted in the heat unit, it is obvious that the lamp will be likely to smoke if not immediately extinguished. This is accomplished by the disk 8 which will pass into the chimney and smother any flame that is existing on the wick of the lamp. A smoky and unsanitary interior of the brooder is thereby prevented.

From the foregoing it will be observed that a very simple and durable automatic alarm has been provided, the details of which embody the preferred form. I desire it to be understood however, that slight changes in the minor details of construction may be made without departing from the spirit of the invention or the scope of the claim hereunto appended.

I claim:

An automatic alarm for incubators comprising a heating unit provided with a chimney, a balancing beam pivotally supported and having a hook arranged at one end and a weight at opposite end, the said hook carrying a pair of disks of different diameters, the smaller disk being disposed below the larger disk, and adapted to extend into the chimney when the said beam is moved on its pivot whereby the said upper disk will rest upon the top of the said chimney and extend beyond the marginal edge thereof, an electric circuit normally open, and having one terminal connected with the said larger disk, and means arranged in the path of movement of the said larger disk to contact therewith for closing the said circuit when the smaller disk is extended into the said chimney.

In testimony whereof I affix my signature in presence of two witnesses.

GEORGE E. BEACH.
